UNITED STATES PATENT OFFICE

103,666

DESIGN FOR A DISPLAY CONTAINER OR SIMILAR ARTICLE

Ernest M. Brogden, Orlando, Fla., assignor to
Bank of The Manhattan Company, Trustee,
New York, N. Y., a corporation of New York

Application August 9, 1935, Serial No. 58,049

Term of patent 14 years

To all whom it may concern:

Be it known that I, Ernest M. Brogden, a citizen of the United States, residing at Orlando, county of Orange, State of Florida, have invented a new, original, and ornamental Design for a Display Container, or Similar Article, of which the following is a specification, reference being had to the accompanying drawing, forming a part thereof, and in which:

Fig. 1 is a perspective view of the article showing my design;

Fig. 2 is a top plan view;

Fig. 3 is a bottom plan view.

The design of my container comprises a tray or body portion having blunt corners, and part-cover members, the latter each having a generally segmental contour in plan and with an outwardly rounded contour in lines transverse to its line of connection with the tray or body portion and all of said members having peripheral edges leaving the top of the container open centrally and at its corners in the closed position of said members.

What is claimed is:

The ornamental design for a display container or similar article as shown and described.

ERNEST M. BROGDEN.
